TROUSER HANGER

John J. Sullivan, 3920 Granby St.,
Norfolk, Va. 23504

Filed Nov. 9, 1971, Ser. No. 197,197

Term of patent 14 years

Int. Cl. D6—08

U.S. Cl. D6—252

FIG. 1 is a side elevational view of a trouser hanger embodying my new design, the opposite side being substantially the same as the side shown;

FIG. 2 is a top plan view thereof;

FIG. 3 is a bottom plan view thereof;

FIG. 4 is a fragmentary left end elevational view thereof with the hook omitted;

FIG. 5 is a fragmentary right end elevational view thereof with the hook omitted;

FIG. 6 is a fragmentary left end elevational view of the hook portion thereof; and

FIG. 7 is a fragmentary right end elevational view of the hook portion thereof.

I claim:

The ornamental design for a trouser hanger, as shown and described.
